202,461
COMBINED ILLUMINABLE SIGN AND
INDICATOR, OR SIMILAR ARTICLE
Carl E. Sederquist, 158 Amherst St.,
Wethersfield, Conn.
Filed Aug. 21, 1963, Ser. No. 76,312
Term of patent 14 years
(Cl. D1—12)

Fig. 2

Fig. 1

Fig. 5

Fig. 1

Fig. 3

FIG. 1 is a front elevational view of a combined illuminable sign and indicator, or similar article, showing my new design;

FIG. 2 is an elevational view taken from the right of FIG. 1;

FIG. 3 is a rear elevational view thereof;

FIG. 4 is an elevational view taken from the left of FIG. 1; and

FIG. 5 is an enlarged fragmentary cross-sectional view taken on line 5—5 of FIG. 1.

I claim:

The ornamental design for a combined illuminable sign and indicator, or similar article, substantially as shown and described.
